UNITED STATES PATENT OFFICE.

FRANK J. RHEAUME, OF SCHENECTADY, NEW YORK.

AIR-VALVE.

1,283,303.

Specification of Letters Patent. Patented Oct. 29, 1918.

Application filed May 11, 1918. Serial No. 233,941.

To all whom it may concern:

Be it known that I, FRANK J. RHEAUME, a citizen of the United States, residing at Schenectady, in the county of Schenectady 5 and State of New York, have invented certain new and useful Improvements in Air-Valves, of which the following is a specification.

In the operation of internal combustion engines, of the type utilizing liquid fuel, it has been discovered that a greater mileage may be obtained from a given amount of fuel by the admission of air into the mixture at a point between the carburetor and the intake of the engine. This has been attributed to a more thorough vaporization of the fuel and the combining with the mixture of air for tempering the same with the result that a less amount of fuel is required for a given amount of mixture.

The purpose of the present invention is to provide a valve of unique structure whereby air in regulated quantity may be supplied to the mixture, such valve being of a construction to be readily applied to any type or make of internal combustion engine.

A further purpose of the invention is the provision of a valve which may be readily applied to or disconnected from the engine and which embodies a needle valve adapted to operate by a reciprocatory movement only, thereby assuring a firm seating of the needle to prevent the seat and the end of the valve from becoming unnecessarily worn.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

In the drawing:—

Figure 1 is a central longitudinal section of an air valve embodying the invention,

Fig. 2 is a transverse section on the line 2—2 of Fig. 1, and

Fig. 3 is a horizontal section on the line 3—3 of Fig. 1 looking in the direction of the arrows.

Corresponding and like parts are referred to in the following description and indicated in the several views of the drawing by like reference characters.

The valve comprises a casing 1 which as indicated is of tubular form and open at both

ends and having the end portions reduced and exteriorly threaded. A hollow extension 2 is provided at one end of the casing 1 and is closed at its outer end, such extension being of circular form and constituting a coupling element. A cap 3 closes the end of the casing 1 adjacent the lateral coupling extension 2 and is provided centrally with an opening 4 for the ingress of air. A chamber 5 is mounted upon the opposite end of the casing 1 and is retained in place thereon by means of a cap 6, such chamber being clamped between the inner end of the cap 6 and the shoulder formed at the inner end of the externally threaded reduced end portion of the casing. A partition 7 is disposed within the casing 1 adjacent the lateral coupling extension 2 and is centrally apertured.

A needle valve 8 is disposed within the casing 1 and is mounted in the partition 7 and the cap 6. One end of the needle valve closes the opening 4 and its opposite end terminates within the chamber 5 and is formed with a depression 9. The valve is provided with a collar 10 which constitutes a stop for one end of a spring 11, the opposite end of such spring obtaining a bearing against the partition 7. The spring 11 is of helical form and expansible and constructed of wire of small gage. The purpose of the spring 11 is to normally unseat the valve thereby permitting air to enter the opening 4 for a purpose and in a manner presently to be explained. A rod 12 is mounted in the outer end of the chamber 5 and its inner end 13 is made rounding so as to fit the depression 9 in the end of the valve 8. The rod 12 constitutes operating means for the valve and extends to a convenient point of operation.

A coupling is provided as means for attaching the valve to the manifold or other part of the engine to which the valve is adapted to be applied. This coupling comprises a split band 14 and a nozzle 15, the latter having an end portion reduced and externally threaded so as to make screw threaded connection with an opening formed in the manifold or other part adapted to receive the coupling. The split band 14 has the separated portions connected by means of a bolt 16 or like fastening whereby provision is had for tightening or loosening the split band as required. The nozzle 15 is provided with a central opening 17 which is adapted to register with an opening 18

formed in the side of the lateral coupling extension 2.

In practice the manifold or other part of the engine to which the valve is to be applied is formed with a threaded opening to receive the threaded end of the nipple 15, and after the coupling, comprising the parts 14 and 15, has been placed in position the casing 1 or body of the valve is fitted to the coupling by having the lateral extension 2 inserted in the split band 14, care being exercised to have the opening 18 register with the opening 17 after which the bolt 16 is tightened so as to clamp the band 14 about the lateral extension 2, thereby holding the valve body or casing 1 in the required position against possible movement. Outward movement of the rod 12 permits unseating of the valve 8 so that air may be passed through the opening 4 into the casing 1, thence through the hollow extension 2, and openings 17 and 18 into the manifold, (not shown) or other part so as to supply an additional amount of air to the gaseous mixture whereby the latter is modified to such an extent as to make it possible to operate the engine with a less amount of fuel with the result that a material saving results and the carbonizing of the engine minimized.

The foregoing description and the drawing have reference to what may be considered the preferred, or approved, form of my invention. It is to be understood that I may make such changes in the construction and arrangement and combination of

parts, materials, dimensions, et cetera, as may prove expedient and fall within the scope of the appended claims.

Having thus fully described my invention, ⁴⁰ what I claim as new and desire to secure by Letters Patent is:

1. An air valve of the character specified, comprising a tubular body having a transverse partition near one end and a lateral ⁴⁵ coupling extension between the partition and the adjacent end, caps closing the ends of the body, the cap adjacent the coupling extension having an opening, a needle valve ⁵⁰ slidable in the cap adjacent the coupling extension, a spring normally tending to hold the valve unseated, a chamber at the end of the body remote from the coupling extension, and a rod mounted in the chamber and in contact with the valve for effecting ⁵⁵ seating thereof.

2. An air valve comprising a tubular body, caps threaded on the ends of said body, a valve slidably mounted within the body, a spring on the valve and normally ⁶⁰ tending to hold the same unseated, a chamber held on the valve body by means of one of said caps, and an operating rod mounted in the chamber and in contact with the valve for seating the same against the tension of ⁶⁵ the spring coöperating therewith.

In testimony whereof I affix my signature in presence of two witnesses.

FRANK J. RHEAUME.
